ELECTROMAGNETICALLY OPERATED SWITCH

Filed July 20, 1942

UNITED STATES PATENT OFFICE

2,344,809

ELECTROMAGNETICALLY OPERATED
SWITCH

John Eaton, Schenectady, N. Y., assignor to General Electric Company, a corporation of New York

Application July 20, 1942, Serial No. 451,522

8 Claims. (Cl. 200—87)

My invention relates to electromagnetically operated switches, more particularly electric relays, and has for its object a simple, reliable and inexpensive electromagnetic switch which is substantially shockproof.

In carrying out my invention in one form I provide a magnetic field structure consisting of a strap of magnetic material having two core legs extending upward from one side with the upper end portions of the legs bent over in substantially parallel relation with the base, one of these pole portions being nearer the base than the other. I also provide a third core leg intermediate the other two on which is mounted a coil and on the end of which is pivotally mounted an armature whose ends in attracted positions engage the outer side of the pole portion nearer the base and the inner side of the pole portion farther from the base.

I also provide plates of electrically insulating material which are secured to the two outer core legs and which form supports for electric terminals leading to the coil, as well as supports for the contact arm and contacts actuated by the armature.

For a more complete understanding of my invention, reference should be had to the accompanying drawing Fig. 1 of which is a plan view of an electromagnetically operated switch embodying my invention; Fig. 2 is a side elevation view of the device shown in Fig. 1; Fig. 3 is an elevation view looking downward on Fig. 1; Fig. 4 is a view in perspective of the pivoted armature; Fig. 5 is a sectional view taken along the line 5—5 of Fig. 4 looking in the direction of the arrows and showing the armature in its attracted position; Fig. 6 is a perspective view to a reduced scale showing the magnetic supporting base and three core legs; Fig. 7 is a view in perspective of a small electrically conducting part for supporting the contact arms and the stationary contacts; while Fig. 8 is an end elevation view of an electrically insulating support.

Referring to the drawing, I have shown my invention in one form as embodied in an electric relay. It is provided with a base member 10 (Fig. 6) in the form of a strap or strip of unlaminated magnetic material such as iron, having sufficient cross section to carry the desired amount of magnetic flux. On opposite ends of the base 10 are the core legs 11 and 12 which are integral with the base and bent upward in parallel relation with each other and at right angles with the base, as shown in Fig. 6. On their ends these core legs have transversely extending por-

tions 13 and 14 provided respectively with outer and inner pole faces.

Midway between the core legs 11 and 12 is a middle core leg 15 which is cylindrical and has its lower end secured to the base 10. This leg also extends in substantially parallel relation with the legs 11 and 12. An exciting or operating coil 16 surrounds this middle leg and is held against the base 10. Also, the flat armature 17 is pivotally mounted on the end of this central core leg 15 so that a laterally offset end 17a on the armature projects under the pole portion 14 while the opposite end 17b of the armature is directly above the pole portion 13. Thus, when the coil 16 is energized, the armature is rotated through a small angle on the central leg 15 as a pivot by reason of the attraction of the transverse pole pieces for the opposite ends of the armature. The armature comes to rest with opposite sides of its two ends engaging pole faces on opposite lower and upper sides of the pole portions 13 and 14.

For the purpose of holding the armature in a central position on the end of the pole leg 15, a yoke member 18 is provided having an aperture 18a (Fig. 5) in its base through which extends the smaller upper end of the leg 15, the yoke 18 resting and being swiveled on a shoulder 19 (Fig. 6) formed on the leg 15 at the junction of the smaller upper end. Secured to opposite sides of the armature 17 are central laterally extending positioning trunnions 20 and 21 which respectively fit in slots 20a and 21a in the yoke 18 provided for these trunnions. The slots are substantially parallel with the central core leg 15. The engagement of the trunnions with the side walls of the slots and with the sides of the yoke definitely positions the armature centrally on the end of the core leg 15 while providing for pivotal movement on the core leg in the plane of the core leg as well as for the required small amount of transverse pivotal movement of the yoke on the core leg for adjustment purposes or for equalization purposes to prevent binding of the parts.

A spring retaining plate or clip 22 is provided to hold the yoke 18 in position. This clip extends between the upstanding arms of the yoke and bears upon its base, as seen in Figs. 2 and 5. It has an elongated aperture 22a through which the end of the core leg 15 extends. One end, as seen in Figs. 1 and 2, projects underneath the pole portion 13 and is held depressed by the pole portion. The opposite end or upper end, as seen in Figs. 1 and 2, is provided with

a narrow portion 23 which projects through an aperture provided for it in a supporting end plate 24 made of suitable electrically insulating material such as a fibre or a molded compound.

This support 24 is secured to the core leg 12 by means of lugs 25 and 26 on the outer edge of the pole leg. These lugs extend through apertures provided for them in the support 24 and pins 27 and 28 extending through apertures in the lugs. These pins are furthermore wedge shaped, i. e. one end is smaller than the other, so that when they are driven into the holes in the lugs they force the support 24 tightly against the outer end or edge of the pole leg 12. A similar electrically insulating plate support 29 is secured to the other core leg 11 in the same manner as the support 24 by means of lugs 30 and 31 on the leg 11 and wedge pins 32 and 33 extending through the lugs.

To provide for a pivotal mounting of the armature, the upper end of the central core leg 15 which, as shown, is a solid unlaminated rod of magnetic material provided with a plane surface parallel with the base 10. Also, the armature 17 is actually, as shown, made of two unlaminated plates or layers 34 and 35. The plate 35 is provided with an aperture 36 (Fig. 5) through which the upper end of the leg 15 extends into engagement with the inner surface of the outer or upper plate 34. In order to provide a knife-edge pivot bearing extending transversely of the armature about which the armature is balanced, a semi-circular portion 37 on the metal of the plate 34 forming a supporting portion is stuck outward pivotally about its diameter. This portion 37 has a radius somewhat larger than the radius of the leg 15 so that when the armature moves to its unattracted position shown in Fig. 2, the semi-circular wedge shaped space or recess provided by the pressed out portion 37 encloses one half of the upper end of the pole leg. It will thus be seen that the diametric junction line between the portion 37 and the plate 34 forms a knife-edge bearing 38 (Fig. 5) which rests on the upper end of the leg 15 and extends diametrically thereof. This bearing 38 is, of course, free to shift angularly in the plane of the upper end of the leg to take care of such adjustment as may be necessary for the assembly of the parts together. Moreover the armature is statically balanced about the bearing 38 so that the armature is substantially unaffected by shocks such as may be applied to the support on which the device is mounted.

Also mounted on opposite sides and ends of the armature 17 are outer and inner transverse bars 39 and 40 made of electrically insulating material such as fibre or a molded compound, these bars being secured to the armature by suitable rivets 39' and 40' which hold the plates of the armature together as well. Each of these bars operates a spring contact arm at each end. Thus, the outer bar 39 operates the contact arms 42 and 43 while the bar 40 operates the arm 44, shown in Fig. 2, and another similar contact arm (not shown) similarly mounted at the opposite end of the bar 40. Each contact arm is operatively connected to a cross bar by means of a slot 45 in the contact arm through which extends a T-shaped member 46 transversely with respect to the slot. The outer cross member on the T member 46 is shorter than the length of the slot 45 so that by turning the two parts at right angles to the positions shown in Fig. 1 the T part can be inserted through the slot. This connec-

tion has the advantage that it provides for limited longitudinal freedom of movement between the cross bar and each contact arm during the opening and closing movement.

On their movable or upper ends, as seen in Figs. 1 and 2, the arms 42 and 43 carry electric contacts 47 and 48, while their opposite ends are secured to the support 29. As shown, the arm 43 is secured to the support by providing an end portion 49 of reduced width leaving shoulders at its junction with the main portion, which end portion is slipped sidewise into a slot 50 in the support 29. This slot 50 joins with a rectangular hole 51 (Fig. 8) through which extends a relatively stiff supporting member 52 shown in Fig. 7.

In the assembly of the spring arm 43 and supporting member 52, and also other similar parts, the spring arm 43 and the member 52 are first preformed by bending their ends toward the left, as viewed in Fig. 2. The member 52 is assembled first on the insulating support 29, the elongated bent shank portion being inserted through the hole 51 and the projections 53 engaging the inner side of the support 29. Preferably, the laterally bent portion of the member 52 is then compressed firmly on the support 29 so that the support is clamped between this laterally extending end and the projections 53. To facilitate the bending of the member 52, a small aperture 54 is provided in it at the bend. Next the preformed switch arm 43 is slipped sidewise through the slot 50 to a position under the member 52. Electrical connections are made to the contact arm 43 by soldering the connection to the ends of the parts 52 and 43, this connection being facilitated by providing aligned notches 55 in these parts. Moreover, the end of the spring arm is thus secured by the soldering operation to the member 52 whereby the spring arm is held securely in place.

The contact arm 42 is similarly secured to the support 29 at the same distance from the base 10 as the arm 43 in the same manner as the arm 43 is secured to the support. Also, the contact arm 44 has its end secured in this manner to the support 24 but considerably nearer the base 10 so that this contact arm is engaged by the right-hand side of the cross bar 46, as seen in Fig. 2. The contact arm corresponding to the arm 44 is likewise secured in this way to the support 24.

The supporting members 52 are also utilized as supports for the stationary contacts. Thus, the stationary contact 56 (Fig. 2) with which the contact 48 cooperates is mounted on a member 57 having the same construction as the member 52 of Fig. 7. In this case, a rectangular hole only without a slot is provided in the support 24 through which the preformed member 57 is inserted and secured to the support 24. This same supporting construction is utilized for the contact supports 58 and 59 as shown in the drawing. The spring contact arms are shaped so as to bias their movable contacts to open circuit positions and bias the armature to its unattracted position as shown in Fig. 2.

Preferably the contact arms and stationary contacts are assembled to the supports 24 and 29 before the supports are assembled in the core legs 11 and 12.

A spring member 60 is provided to bias the armature toward the end of the leg 15, the lower end as seen in Fig. 2, of this member being bent to the right and engaging the armature substantially at its pivot center and applying a force to it. The other end of the member 60 extends

through the support 24 in the same aperture as the lug 25, it being provided with a lug 61 having substantially the same shape as the lug 25 and with an aperture through which the pin 27 extends. Also, the member 60 is provided with two upturned flanges 62 and 63 (Fig. 1) on opposite sides the upper ends of which, as seen in Figs. 1 and 2, engage the inner or lower side of the support 24 so as to hold the member 60 securely in place.

The end of the armature which is adjacent the longer core leg 12, i. e., the upper end as seen in Figs. 1 and 2, is laterally offset away from the leg 12 thereby to provide a magnetic flux insulating air gap between the side edge of the armature and the core leg 12. This effectively prevents any appreciable leakage flux from passing directly from the core leg 12 to the adjacent edge of the armature and thereby prevents any consequent lateral force applied to the armature by magnetic attraction for the core leg 12.

The insulating supports 24 and 29 likewise support the electric terminals 64 and 65 of coil 16, these terminals extending through suitable apertures provided for them in the supports.

Lugs 66 and 67 are provided on the base for securing the base to a support on which the relay is mounted.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

What I claim as new and desire to secure by Letters Patent of the United States is:

1. An electromagnetic device comprising an elongated member of magnetic material forming a base, long and short core legs secured to one side of said base, a transverse pole portion on the end of each of said core legs extending substantially parallel with said base and transversely with respect thereto, said pole portions being spaced different distances from said base, a middle core leg between said first two core legs, an armature member pivotally mounted on said middle core leg and pivotally movable to an attracted position in which opposite sides of said armature engage inner and outer sides of said pole portions on said short and long legs respectively, said armature having a portion on its end adjacent said long core leg laterally offset away from said long core leg to provide a magnetic flux insulating air gap between said armature and said long core leg, and a winding on said middle leg for moving said armature when energized to said attracted position.

2. An electromagnetic switch comprising an unlaminated base member made of magnetic material having two core legs bent upward from one side of said base in substantially parallel relation with each other, each of said core legs having its end bent over in parallel transverse relation with respect to said base to form two pole members, a pair of lugs projecting from the outer edge of each of said core legs, a plate of electrically insulating material on the outer edge of each of said core legs provided with apertures through which said lugs extend, said lugs being provided each with a transverse aperture, tapered pins extending through said apertures on the outer side of each of said plates thereby to clamp said plates against said core legs, electric switch-

ing means carried by said plates, a middle core leg between said first two core legs secured to said base, an operating coil mounted on said middle core leg, and an armature pivotally mounted on the end of said middle core leg having its ends movable into engagement with said pole pieces when said coil is energized, and an operating connection between said armature and said switching means.

10. 3. An electromagnetic device comprising a magnetic core provided with at least three substantially parallel core legs each having one end connected to a cross core member, a transversely extending plane surface on the other end of said middle core leg, a platelike armature mounted on the end of said middle core leg, said armature having a recess terminating in a line extending transversely of said armature to form a knife-edge bearing engaging said plane surface about which bearing said armature is balanced, and an operating coil on said middle core leg for moving said armature pivotally to an attracted position.

4. An electromagnetic device comprising a magnetic core provided with at least three substantially parallel core legs each having one end connected to a cross core member, said middle core leg having a smaller cylindrical portion on its end providing a shoulder, a yoke provided with an aperture for said smaller end mounted on said shoulder with outwardly extending arms provided with slots, a platelike armature extending between said arms, trunnions on opposite sides of said armature lying in said slots whereby said armature is swiveled on the upper end of said middle core leg, and an operating coil on said middle core leg for moving said armature pivotally to an attracted position.

5. An electromagnetic device comprising a magnetic core provided with at least three substantially parallel core legs each having one end connected to a cross core member, a transversely extending plane surface on the other end of said middle core leg and said middle core leg having a smaller cylindrical portion on said end providing a shoulder, a yoke provided with an aperture for said smaller end mounted on said shoulder with outwardly extending arms provided with slots, a platelike armature extending between said arms, trunnions on opposite sides of said armature lying in said slots whereby said armature is swiveled on the upper end of said middle core leg, said armature having a semi-circular recess whose diameter extends along the transverse center of mass of said armature and forms a knife-edge bearing resting on said plane surface, and an operating coil on said middle core leg for moving said armature pivotally to an attracted position.

6. In an electromagnet, a core leg provided with a transversely extending plane bearing surface on one end, an armature having a plate-like supporting portion mounted on said bearing surface, said supporting portion having a recess terminating in a line extending transversely with relation to said bearing surface to form a knife-edge bearing engaging said bearing surface on which said armature is pivotally movable, said recess forming a space into which said end of said core leg extends during pivotal movement of said armature.

7. In an electromagnet, a core leg having a smaller cylindrical portion at one end providing a shoulder, said end being provided with a transversely extending plane bearing surface, a yoke provided with an aperture for said smaller end

mounted on said shoulder, and said yoke being provided with outwardly extending arms provided with openings, a plate-like armature extending between said arms, trunnions on opposite sides of said armature extending into said openings whereby said armature is swiveled on said plane bearing surface, said armature having a recess terminating in a line extending transversely with relation to said bearing surface to form a knife-edge bearing engaging said bearing surface on which said armature is pivotally movable.

8. An electromagnetic switch comprising an unlaminated base member made of magnetic material having two core legs bent upward in substantially parallel relation with each other, each of said core legs having its upper end bent over in parallel transverse relation with said base to form two pole members spaced different distances from said base, a pair of lugs projecting from the outer edge of each of said core legs, a plate of electrically insulating material on the outer edge of each

of said core legs secured to said lugs, said plates being provided with slots positioned opposite each other in a direction substantially parallel with the plane of said core legs, a spring contact arm having one end secured in one of said slots and extending to a point adjacent the second of said insulating plates, a contact supporting member secured in the second of said slots provided with a stationary contact on the inner side of said second plate, a middle core leg between said first two core legs secured to said base, an armature pivotally mounted on the end of said middle core leg having its ends movable into engagement with said pole pieces when said coil is energized, a cross bar made of electrically insulating material secured to said armature, a loose connection between said cross bar and said spring contact arm for movement of said contact arm by said armature into and out of engagement with said stationary contact.

JOHN EATON.
